LENS AND METHOD OF MANUFACTURING
THE SAMEEdward H. Titmus, Petersburg, Va., assignor to
Titmus Optical Company, Petersburg, Va., a
corporation of Virginia

Application November 6, 1936, Serial No. 109,603

5 Claims.

The present invention relates to lenses and methods of manufacturing the same. A primary object of the invention is to provide a compound lens blank which will permit the measurement of the thickness of the lens section being ground without removing the blank from the grinding holder.

Another object of the invention is to provide a compound lens blank which will permit the measurement of each of the lens sections thereof during the grinding of said sections, without removing the blank from the grinding holder.

A further object of the invention is to provide a method of manufacturing a lens blank having the above advantages, and a method of finishing such a blank into a lens.

Various other objects of the methods and article disclosed herein will be apparent as the specification progresses.

20 In the drawing, which discloses a form of the article of the present invention, and illustrative methods whereby the blank may be formed and finished, which drawing is in no sense restrictive:

25 Figure 1 is a top plan view of a lens blank of the present invention, showing one of the lens sections broken away to illustrate the construction of the blank.

30 Figure 2 is a vertical sectional view through a lens grinding device, showing the compound lens in position for concave grinding.

35 Figure 3 is a vertical sectional view of another grinding device, with the compound lens positioned for convex grinding.

Figure 4 is a vertical sectional view taken diametrically through the lens blank, after the same has been ground.

Figure 5 is a similar vertical sectional view through the finished lens.

The ophthalmic lens disclosed in the drawing is one of the compound type, comprising what I will term for convenience "a first lens section" 10 and a "second lens section" 12, secured together by any appropriate adhesive material 14. This adhesive material is of the type having a sufficient toughness and adequate gripping qualities when applied to glass surfaces for immovably securing lens sections together, and which will aid in reinforcing the sections against shattering or breaking. The adhesive material will be of such transparency that it will not impede the passage of rays of light through the lens. While I have shown in the drawing a compound lens of the type in which the lens sections 10 and 12 are alike in size, it will be obvious from the following description that the invention may be

(Cl. 88—54) applied in the manufacture of compound lenses, such as bifocal lenses or other types, in which one lens section is not entirely coextensive with the other lens section.

The lens sections 10 and 12 are shown having engaging surfaces of complementary curvature, and it will be understood that the term "complementary curvature" may mean that the engaging faces of said lens sections are flat planes in a special case.

In the manufacture of lenses, it is common to take a lens blank of approximate form, and secure the same to a holder, which holder is rotated relatively to a grinding tool while a face of the lens is being ground. During the grinding operation, the edges of the blank may extend outwardly beyond the periphery of the grinding tool, so that the thickness of the lens may be measured. It has also been the custom to provide slots in the edge of the lens holder to receive calipers for measuring the thickness of the lens during the grinding operation. In grinding lens blanks having only a single section, holes have been drilled into the blank to a depth indicating the amount of glass to be removed, and when grinding has been performed to this depth, the disappearance of the hole indicates that the lens is ground to proper thickness.

None of these methods are practical in the manufacture of compound lenses of the type disclosed in the present application, in which it is desirable to control the thickness and contour of a section of a compound lens being ground, or each of the sections of a compound lens when both are being ground, without removing the blank from its holder during the grinding operation.

In Figure 1, the first lens section 10 is shown provided with a pair of diametrically opposed notches or apertures 16 extending entirely through the thickness thereof, while the second lens section 12 is likewise provided diametrically opposed apertures 18 also extending entirely through the thickness of said section.

The lens sections are assembled and adhesively secured to one another with the apertures staggered 90° from the apertures 18, so that a portion of each lens blank will overlie the aperture in the edge of the opposed lens blank. It will be noted that the edge of each lens section adjacent where it overlies the opening in the engaging lens section does not extend beyond the edge of said engaging lens section, so that the measurement of the particular lens section is taken in the opening in its engaging lens sec-

tion, the adjacent portions of the edge of the overlying lens section not being free to be engaged by calipers or the like. I term this condition of the edge of the lens section adjacent its overlying portion as "underlying" the edge of the engaging section which has the opening therein, in the sense that the edge of the adjacent portion is covered so that the measurement must be made in the opening. It will be apparent from Figure 1, that the thickness of each lens blank may be measured at diametrically opposed points, by applying calipers or other measuring devices at the openings in the opposed lens sections.

15 While I have disclosed the apertures 16 and 18 in the edge of the respective lens sections, it will be evident that the present invention is not limited to such a disposition. For instance, said apertures might be in the form of holes spaced inwardly from the edge of the blank, preferably close enough to the edge so that when the blank is cut to final size, as hereinafter described, the portion thereof including the apertures will be removed. It will also be evident that the apertures 16 and 18 need not necessarily be spaced a quadrant's distance from each other, although this arrangement is preferable to more accurately control the grinding operation discussed below. Furthermore, as many apertures as necessary may be provided in the lens sections, and said apertures may be as closely spaced as desired, depending on the degree of accuracy necessary in the grinding operation.

The lens blanks described above are to be manufactured in quantities for sale to artisans in the industry who grind the blanks to final form on order. The blanks may be of any size and shape, and the artisans will obviously grind the blanks to various forms.

40 When the blank is to be ground, it is secured to a conventional lens grinding holder 20 shown in Figure 2, said blank usually being cemented to said holder by a quantity of material 22. The lens holder may be maintained in fixed position, or may be rotated with a supporting spindle 24. In Figure 2, the blank is shown disposed upon the holder in position for concave grinding, in which position the first lens section is cemented to the holder so that the second lens section 12 is faced outwardly toward the grinding tool.

The grinding tool 26 may be of any conventional form, said tool usually being rotatably mounted with a supporting spindle 28 driven in any appropriate manner.

55 During the grinding operation calipers or other measuring devices may be applied at any time within the apertures 16 of the first lens section 10 to measure the thickness or contour of the second lens section 12. If the lens is not being accurately ground, as indicated by the measurement at one of the apertures 16, or as indicated by a comparison of the measurements taken at each of the opposed or spaced apertures 16, the relative positions of the lens holder and grinding tool may be adjusted to correct the grinding in a manner well known in the art.

After the inner face of the lens has been ground as discussed above, the blank is removed from the holder 20 and is mounted upon the grinding holder 30 for convex grinding, being secured thereto in any appropriate manner as by cement 32. When the blank is thus mounted for convex grinding, the second lens section 12 is secured to the holder 30, thus presenting the first lens section to the grinding tool 34.

The holder 30 and grinding tool 34 may be mounted on spindles for rotation, and are capable of adjustment with respect to one another to control the grinding operation in a manner well known in the art.

5 During the convex grinding of the first lens section 10, measurements of the thickness and contour of said section may be made without removing the blank from the holder by applying calipers to the blank in the apertures 18 in the second lens section 12. As discussed before, the measurements taken at apertures 18 may be compared in order to determine the adjustment of the holder and grinding tool necessary to correct the grinding operation.

10 After the proper curvature has been imposed upon the convex face of the lens section 10, the blank will be in the condition shown in Figure 4, when a lens of the type used for illustration is being manufactured.

15 To form the finished lens, the peripheral portion of the lens blank including the openings 16 and 18 is cut away, resulting in a lens of the type shown in Figure 5, which is in condition to be mounted.

20 It will be understood that the present methods and article are not limited to use in the manufacture of ophthalmic lenses, but may be of equal utility in making other types of lenses.

25 Various modifications of the article and methods disclosed herein may be made without departing from the scope of the invention.

I claim:

30 1. A lens blank comprising a plurality of engaging lens sections having openings adjacent the edges thereof, each opening extending completely through its respective section, said sections being superposed one upon another and immovably secured together, said openings being of substantial size to receive a measuring device 40 and being offset from one another so that a portion of each lens section overlies an opening in its engaging lens section, the edge of each lens section adjacent its overlying portion underlying the edge of its engaging lens section, whereby 45 the thickness of each lens section may be measured at an opening in its engaging lens section.

35 2. A lens blank comprising a pair of engaging lens sections having substantially diametrically opposed openings adjacent their edges, each 50 opening extending completely through its respective section, said sections being superposed one upon another and immovably secured together, said openings being of substantial size to receive a measuring device, the engaging faces of said sections being of complementary curvature, a portion of one lens section overlying an opening in its engaging lens section, said lens sections being coextensive adjacent said openings, whereby the thickness of each lens section may be 55 measured at an opening in its engaging lens section.

40 3. A lens blank comprising a pair of engaging lens sections having openings adjacent the edges thereof, each opening extending completely 60 through its respective section, said sections being superposed one upon another, and immovably secured together with a thin intermediate transparent web of adhesive material therebetween, said openings being of substantial size to receive 65 a measuring device, the engaging faces of said sections being of complementary curvature, and said sections being superposed in such fashion that an opening in one lens section is substantially a quadrant's distance from an opening in 75

its engaging lens section, a portion of one lens section overlying an opening in its engaging lens section, said lens sections being coextensive adjacent said openings, whereby the thickness of each lens section may be measured at an opening in its engaging lens section.

4. The method of making lenses which comprises forming a plurality of lens sections with openings of substantial size adjacent the edges thereof to receive a measuring device and extending completely through each of said sections, superposing said sections to form a lens blank and immovably securing said sections together with a portion of each lens section overlying an opening in its engaging lens section, and with the edge of each lens section adjacent its overlying portion underlying the edge of its engaging lens section, and grinding the outer faces of each of said sections and controlling the grinding operation in accordance with measurements of the

thickness of said sections taken at said openings.

5. The method of making lenses which comprises forming a plurality of lens sections with openings of substantial size adjacent the edges thereof to receive a measuring device and extending completely through each of said sections, superposing said sections to form a lens blank and immovably securing said sections together with a portion of each lens section overlying an opening in its engaging lens section, and with the edge of each lens section adjacent its overlying portion underlying the edge of its engaging lens section, grinding the outer faces of each of said sections and controlling the grinding operation in accordance with measurements of the thickness of said sections taken at said openings, and finishing the blank into a lens by removing a peripheral portion therefrom which includes said openings. 5

EDWARD H. TITMUS. 20
